DESIGN FOR SHOULDER PADS

Florence May O'Brien, Los Angeles, Calif.

Application October 11, 1944, Serial No. 115,707

Term of patent 3½ years

(Cl. D3—31)

To all whom it may concern:

Be it known that I, Florence May O'Brien, residing at Los Angeles, in the county of Los Angeles and State of California, have invented a new, original, and ornamental Design for Shoulder Pads, of which the following is a specification, reference being had to the accompanying drawing, forming a part thereof.

The figures in the drawing are Fig. 1, a top perspective view, and Fig. 2 an end perspective view of a pair of shoulder pads showing my new design.

I claim:

The ornamental design for shoulder pads, as shown.

FLORENCE MAY O'BRIEN.
